AUTOMATIC MACHINE FOR PROCESSING THERMIONIC TUBES AND THE LIKE

Henry W. Parker and Joseph R. Eakins, Toronto,
Ontario, Canada, assignors to Rogers Radio
Tubes, Ltd., Toronto, Ontario, Canada, a cor-
poration of Canada

Application September 10, 1932, Serial No. 632,505

7 Claims. (Cl. 91—12.2)

Our invention pertains in general to automatic machinery for use in the manufacture of electron tubes and the like and specifically relates to an automatic machine for treating the containing envelopes and bases of such tubes.

In the manufacture of certain types of electron tubes and the like, a metallic coating is exteriorly affixed to a predetermined portion of the glass tube envelope and often to the side walls of the tube base. In the process of applying this metallic coating, the tube is first put in a condition for best receiving and retaining the coating. This is accomplished by subjecting the tube to a blast of abrasive particles in order to roughen the required area of the surface. This roughened surface of the tube is then subjected to a forced spray of the metallic coating material whereby a uniform metallic coating is applied to the required surface area of the tube. Various difficulties have been encountered in this process and it is one of the objects of our invention to produce a machine for preparing tubes and applying thereto a metallic coating in an efficient automatic operation which overcomes difficulties heretofore encountered.

Another object of our invention consists in producing an automatic tube coating machine in which mechanical parts upon which metallic sprays and sand blasts would have a deleterious effect are entirely removed from the vicinity of such actions.

A further object comprises providing an automatic tube coating machine for processing a tube surface in a continuous operation whereby a restricted area of the tube envelope is first subjected to an abradant action and then coated by a spraying action, means for restricting the area of the tube envelope subject to such actions being continuously employed during the process to avoid non-uniformity of the treated area.

A still further object consists in providing a method of manufacturing coated tube surfaces in a continuous automatic process involving simple and efficient apparatus.

These and other objects will be apparent in the following, reference being had to the accompanying drawings in which like reference numerals designate corresponding parts throughout, and in which:

Fig. 1 is a general view of one embodiment of the automatic tube machine of our invention;

Fig. 2 is a partial rear view of the machine represented in Fig. 1; and

Fig. 3 is a transverse sectional view of a con-

structional detail of the tube machine of our invention.

Our invention contemplates providing an automatic tube coating machine employing a multiplicity of tube supporting units which are mounted upon a moving platform for subjecting the tubes to an abradant action and then to a spraying action in a continuous automatic operation. It is an especial feature of our invention that the tube supporting units each provide means for supporting the tube and for defining the restricted area of the tube envelope to be treated by both operations of abradant blasting and metal spraying. The tube supporting units of our invention are rotatably mounted upon a moving platform continuously moving through disjunct regions of processing actions for preparing the restricted area of the surface of the tube and for applying a metallic coating exactly within the confines of that restricted area. The regions of the processing action respectively include an abrasive blasting unit and a metal spraying unit, mechanical means being provided to cause the movement of these units with respect to the tube to ensure complete and proper processing. All of the mechanical elements are so situated and defined in our automatic tube machine that gears, bearings and other parts apt to be deleteriously affected by the abradant blasting and spraying operations are situated externally of the regions of these operations.

Referring to the drawings in detail, and particularly to Fig. 1, there is provided a main-frame 1, including transverse members 3 and 4 through which a shaft 2 is journaled. The lower end of the shaft 2 terminates in a circular platform 5, the upper end of the shaft 2 being provided with a worm-wheel 6 engaging with a worm-gear 7. The worm-gear 7 is mounted upon a shaft 8 journaled in suitable bearings and is provided with a worm-wheel 9 engaging with worm-gear 11. The worm-gear 11 is mounted upon a shaft 12 journaled in suitable bearings and provided with large and small pulley wheels 13 and 14, respectively. The pulley wheel 13 is rigidly secured to the shaft 12 while the pulley wheel 14 is floating thereon. A belt is provided between pulley wheel 13 and a pulley wheel 16 provided on the armature shaft of the motor 17. Another belt is provided between the pulley wheel 14 and a pulley wheel similar to the pulley wheel 16 also mounted on the armature shaft of motor 17.

Consideration will now be given to the tube supporting unit employed in our automatic tube

machine and shown in detail in Fig. 3. Referring to Fig. 3, a circular base 20 is provided with two oppositely positioned upstanding rods 21 and 22. The center portion of the base 20 includes a hollow boss 23 upon which a tube, such as tube 24, may be mounted, it being seen that the base 24b of the tube 24 rests upon the boss and the terminal pins of the tube extend within the hollow portion thereof. The external portion of the tube 24 to be treated includes the exterior of the base and the exterior of the tube envelope proper up to, but not including, a small area at the top of the envelope in which a metallic terminal 24c is provided. It is important in 10 coating the tube that this area remain unexposed to the processing operation, thereby ensuring that none of the conducting coating material approach the terminal 24c.

According to our invention, a cup 25, composed 20 of a resilient material such as rubber, is secured in a member 26 mounted between two sleeves 27 and 28 adapted to slide over the rods 21 and 22, respectively. When the sleeves 27 and 28 are positioned upon the rods 21 and 22, 25 the weight of member 26 causes the cup 25 to annularly engage the upper surface of the tube 24 and protect the area surrounding the terminal 24c from exposure to the abradant and coating operations. The base 20 is provided with a hole 30 for making a running fit with anyone of a plurality of bearing members 30 positioned around the outer edge of the platform 5 (see Fig. 1).

In the operation of the system of our invention, the cup 25 remains upon the tube 24 during the entire processing, thereby ensuring that the area subjected to the sand blasting operation will exactly coincide with the area subjected to the coating operation, thus avoiding any dissymmetry in the finished product. It will be noted that sleeves 27 and 28 cover the areas of the rods 21 and 22 upon which the sleeves 27 and 28 slide and therefore avoid damage which might result from exposure to the abradant and coating actions. The bearing member 30 is also 45 protected from such actions by the proximity of the base member 20.

Referring again to Fig. 1, it will be seen that the tube supporting units are mounted upon the bearing members 30 of the platform 5. The 50 rotation of platform 5 is effected through shaft 2 driven by previously mentioned gears coupled with motor 17. The main-frame 1 supports two enclosed compartments generally indicated at 32 and 33. The platform 5 rotates through both 55 of these compartments, suitable openings being provided so that the tube supporting units on the platform 5 can pass therebetween. Compartment 32, which encloses the region of the abradant blasting operation, may be better seen 60 by reference to Fig. 2.

Referring to Fig. 2, there is provided a nozzle 34 mounted upon a member 35 depending from a walking beam 36. The nozzle 34 is connected through a hose 37 with means for supplying a 65 forced blast carrying abrasive particles, such as sand. The equipment for supplying such a forced abradant blast may be of any desired type and fixtures incidental to such equipment are shown in part in Fig. 1, being generally indicated by reference number 40. Beneath the compartment 32 a hopper 39 is provided for storage of the abrasive material.

Referring again to Fig. 1, a spraying unit 41 is provided within the compartment 33 and 70 mounted upon a member 42 depending from a

walking beam 43. The spraying unit 41 may be any desired device for producing a forced spray of a metallic coating and is provided with connections to suitable supply equipment.

Shafts 45 and 46 are journaled in suitable 80 mountings and hang within the compartments 32 and 33, respectively. The lower extremities of shafts 45 and 46 are provided with disks 47 and 48, respectively, the peripheries of which are provided with a resilient material such as rubber. Shafts 45 and 46 are so positioned that when the platform 5 is rotated the base member 20 of the tube supporting units carried by platform 5 will come into engagement with the disks 47 and 48. The shafts 45 and 46 driven by motor 17 through suitable intermediate gearing including pulley wheel 14, impart rotary motion to the tube supporting units coming into engagement therewith as the platform 5 is revolved. It will be noted that the position of the disks 47 and 48 causes the tube supporting units engaging therewith to be rotated directly in proximity to the sand blasting nozzle 34 in compartment 32 and the spraying unit 41 in compartment 33. The walking beams 36 and 43, from which the blasting nozzle 34 and spraying unit 41 depend, are pivoted at 60 and 61 respectively. The extremities of the walking beams 36 and 43 peripherally engage cams 62 and 63 mounted in shafts 12 and 8, respectively. Rotation of cams 62 and 63 90 through the intermediate gearing driven by motor 17 imparts an oscillating movement to the walking beams 36 and 43 thereby causing the blasting nozzle 34 in compartment 32 and the spraying unit 42 in compartment 33 to move 100 in a reciprocative motion vertically relative to the tubes carried by the tube supporting units in proximity thereto. During such reciprocative motion the disks 47 and 48 cause the tube supporting units proximate to the blasting nozzle 115 34 and to the spraying unit 41 to be rotated whereby the tubes supported thereby are subjected to a thorough and uniform processing action over the required areas thereof. Vents 48 and 49 are provided in compartments 32 and 33 120 and connect with suitable apparatus for removing accumulations from these compartments. In the operation of our automatic tube machine, an operator may be positioned at a point indicated as "A" for placing and removing tubes as 125 the platform 5 rotates. The entire operation of blasting and coating the tube is continuous and automatic, the proper processing of the tube being ensured under automatic control.

Although we have shown a preferred embodiment of the automatic tube machine of our invention, it will of course be obvious that various modifications and changes therein will readily occur to those skilled in the art upon an understanding of our disclosure, but which will not be 130 apart from the intended scope of our invention. We do not therefore desire to limit ourselves to the foregoing except insofar as may be pointed out in the appended claims.

What we claim as new and original and desire to secure by Letters Patent of the United States is:

1. A processing system comprising, means for producing disjunct regions of processing actions, a platform for supporting and moving a plurality 145 of object supporting units through said regions, each of said object supporting units consisting of a base provided with a plurality of standards and an object retaining member provided with a plurality of sleeves for engaging said standards 150

respectively, said sleeves being each of substantially the same length as said standards, means within said regions for imparting mechanical motion to said object supporting units one at a time while said units are passing through the respective processing regions, said mechanical motion being in addition to the movement of said platform and for the purpose of subjecting a supported object to the even and thorough action of the processing region through which the object is passing.

2. A processing system in accordance with claim 1, in which each of said object supporting units comprises resilient means adapted to be affixed to a desired area of a supported object to protect that area from said processing actions.

3. A processing system in accordance with claim 1, in which said processing actions are individually abradant and spraying.

4. An automatic processing machine for electron tubes and the like comprising, a rotatable platform, a plurality of tube supporting units pivotally mounted on said platform, each of said tube supporting units comprising, a base provided with a plurality of standards and an object retaining member provided with a plurality of sleeves for engaging said standards respectively, said sleeves being each of substantially the same length as said standards, an abradant blasting device situated upon one side of said platform, a spraying device situated on the other side of said platform, said last two mentioned devices being so situated as to produce disjunct regions of abradant and spraying actions, a motor, gears coupling said motor with said platform for causing the rotation thereof whereby said tube supporting units sequentially pass through said abradant and spraying regions, said motor and said gears being located above said abradant and

spraying regions, rotatable devices within said regions for imparting rotary motion to said tube supporting units and gearing located above said abradant and spraying regions and interconnecting said motor and said rotatable devices for effecting the rotary motion thereof.

5. An automatic processing machine in accordance with claim 4 including means operated by said motor for causing the reciprocative movement of said abradant blasting device and said spraying device with respect to said tube supporting units within their respective regions of action.

6. An automatic processing system in accordance with claim 4 in which each of said tube supporting units includes resilient means adapted to be attached to a desired surface of a tube supported thereby to protect that area in the same extent from both abradant and spraying actions.

7. A processing machine comprising, means for supporting and moving a plurality of object supporting units, separate means for sequentially producing an abradant action and a spraying action in the path of movement of said object supporting units each of said object supporting units comprising upper and lower members for engaging an object therebetween and means for restricting the area of said object subjected to said abradant and spraying actions to the portion of said object not engaged by said upper and lower members, means for automatically imparting additional motion to said object supporting units only in the regions of said abradant and spraying actions whereby the exposed surfaces of the objects supported by said object supporting units are uniformly exposed to each of said actions.
